(57) **CLAIM**

We claim the ornamental design for a remote control unit for a model vehicle, as shown and described.

DESCRIPTION

FIG. 1 is a perspective view of a remote control unit for a model vehicle taken from the front, top and right side; FIG. 2 is a perspective view thereof taken from the rear, top and left side;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a perspective view thereof taken from the bottom, front, and right side; and,

FIG. 10 is a perspective view thereof taken from the bottom, rear, and left side.

The broken lines represent portions of the article that form no part of the claim.
